SET OF CHESS PIECES

Murray Laufer, 35 E. 85th St.,
New York, N.Y. 10028

Filed June 5, 1969, Ser. No. 17,536

Term of patent 14 years

Int. Cl. D21—01

U.S. Cl. D34—5

FIG. 2

FIG. 1

FIG. 1 is an elevational view of the set of chess pieces showing my new design; the side of the pieces not shown being the same as that of the side shown; and

FIG. 2 is a top plan view of the same.

I claim:

The ornamental design for a set of chess pieces, substantially as shown and described.
